(57) **CLAIM**

The ornamental design for a supply receptacle system, as shown and described.

DESCRIPTION

FIG. 1 shows an assembled front perspective view of a supply receptacle system in accordance with the present invention;

FIG. 2 shows an assembled front elevation view thereof;

FIG. 3 shows an assembled rear elevation view thereof;

FIG. 4 shows an assembled right side elevation view thereof;

FIG. 5 shows an assembled left side elevation view thereof;

FIG. 6 shows an assembled top elevation view thereof;

FIG. 7 shows an assembled bottom elevation view thereof;

FIG. 8 shows a disassembled perspective view thereof;

FIG. 9 shows a disassembled exploded perspective view thereof;

FIG. 10 shows a disassembled inner perspective view of a supply receptacle shell thereof;

FIG. 11 shows a disassembled outer perspective view of the supply receptacle shell thereof;

FIG. 12 shows a closed front perspective view of a supply receptacle pod thereof;

FIG. 13 shows a closed front elevation view of a supply receptacle pod thereof;

FIG. 14 shows a closed rear elevation view of a supply receptacle pod thereof;

FIG. 15 shows a closed right side elevation view of a supply receptacle pod thereof;

FIG. 16 shows a closed left side elevation view of a supply receptacle pod thereof;

FIG. 17 shows a closed top elevation view of a supply receptacle pod thereof;

FIG. 18 shows a closed bottom elevation view of a supply receptacle pod thereof;

FIG. 19 shows an open front perspective view of a supply receptacle pod thereof;

FIG. 20 shows an assembled sideways front perspective view thereof and its intended environment;

FIG. 21 shows an assembled sideways front perspective view thereof in its intended environment;

(Continued)

FIG. 22 shows an assembled sideways front elevation view thereof in its intended environment;
 FIG. 23 shows an assembled sideways back elevation view thereof in its intended environment;
 FIG. 24 shows an assembled sideways right elevation view thereof in its intended environment;
 FIG. 25 shows an assembled sideways left elevation view thereof in its intended environment;
 FIG. 26 shows an assembled sideways top elevation view thereof in its intended environment;
 FIG. 27 shows an assembled bottom elevation view thereof in its intended environment; and,
 FIG. 28 shows an assembled sideways front elevation view thereof in its intended environment.
 The broken lines in the drawings depict unclaimed environmental subject matter and unclaimed portions of the supply receptacle system. The broken lines in the drawings form no part of the claimed design.
